GAME DISK

Elmer W. Christy, Cincinnati, Ohio

Application May 8, 1942, Serial No. 442,211

3 Claims. (Cl. 273—128)

The present invention relates to an improved disk for hand projected and directed slidable movement over a playing surface.

An object of the invention is to provide a game disk for use by children and adults and which is arranged with thumb and finger holes positioned with relation to the vertical axis and the center of gravity so as to afford comfortable gripping and easy and balanced control by the user.

Another object of the invention is to provide in a game disk an arrangement of a number of sets of thumb and finger holes of different spacing but of equal balance so arranged about a vertical center of the disk as to afford a wide variety of grips accommodating the disk to various sizes of players' hands and to peculiarities of muscular or nervous tendencies in gripping the disks.

Still another object of the invention is to provide a game disk of the character described which has its center of gravity disposed low in the mass so as to encourage the use of the muscles of the hips, knees and ankles in the proper and successful directive projection of the disk while the hand which delivers the disk itself is entirely free from skill-deterrent influences.

These and other important objects are attained by the means described herein and disclosed in the accompanying drawing, in which:

Fig. 1 is a top plan view of a game disk embodying the invention.

Fig. 2 is a cross sectional view taken on line 2—2 of Fig. 1.

The disk 5 may be of wood, molded composition or other material of suitable weight and texture. The disk is circular in plan and its edge thickness is rounded on a radius equal to that of its circumference, thus forming a rounded nosing 6 to minimize damage from collision in playing or in handling. The bottom face 7 is flat and smooth and the top surface may be either partly or completely parallel with the bottom face 7. In this embodiment the center 8 of the top face is higher than the remainder of said surface and it is provided with a depressed area 9 of geometric outline and this latter area 9 is distinctively colored so that several disks used in the game may be easily distinguished from one another. A vertical center bore 10 extends entirely through the disk 5 for receiving a rod or a cord whereby a set of such disks is conveniently held together for handling, storage or shipping.

Sloping downwardly from the circumference of center area 8 is an annular area 11 from which the hereinafter described thumb and finger holes lead inwardly and downwardly in the direction

of the line of the vertical axis of the disk. The axes of the thumb and finger holes are thus convergently directed at angles of about 80° to the plane of the bottom face 7 but the top openings of the holes are at right angles to the axes of the holes. The purpose of inclining the annular area 11 is to facilitate the drilling and rounding of the edges of the holes.

Referring now specifically to the arrangement and disposition of the thumb and finger holes, it will be noted in Fig. 1 that a thumb hole 12 has a uniformly rounded bounding edge 13 at the surface of annular area 11. The rounded edge 13 occurs in all of the hereinafter mentioned holes and is indicated throughout by the same reference numeral. Opposite thumb hole 12 are two fingers holes 14—14, slightly smaller in diameter than the hole 12 but having their centers in a common circle concentric with the center of hole 10. When the first and second fingers of a player's hand are inserted in holes 14—14 and the thumb is inserted in hole 12 it will be found that if the hand is small in size, the disk will be suspended with little or no effort and said disk will be very nicely balanced. The rounded edges not only afford comfort for the natural curving of the non-tensioned hand, but they afford rounded surfaces against which the fingers may be selectively tensioned to a suitable degree to skillfully and easily vary the relation of the flat bottom 7 of the disk to the floor or surface upon which the player stands to slidably project the disk along such floor or surface. Such playing surface (not shown) may be suitably marked with chalk or paint to define a scoring area or objective in any desired fashion. By way of a very practical example, a shuffle board area may be used employing the hand projected disks thereon. This affords excellent exercise for the hips, knees, ankles, arms, wrists and fingers in a very entertaining game, which is less strenuous than bowling, although more of the muscles of the body are involved in the play. In order to slidably project the disk for any great distance without bouncing, the hand of the user must bring the bottom face 7 of the disk very close to the floor or playing surface while forcefully swinging the arm to secure good distance. At the same time the wrist, hand and fingers exert a coordinated movement to control the direction of travel. The spacing of holes 12, 14—14 is arranged uniformly about the center of the disk to accommodate a small hand or a short fingered hand. It is an especial object of the invention to provide several sets of thumb and finger holes having different spacings to accom-

modate several sizes of players' hands using what might be called a normal grip employing the thumb and first two fingers. The arrangement of the several sets of holes, however, enables the use of other than the so-called normal grip and in such case the player has the opportunity to use four fingers, three fingers, two fingers, or even one finger, together with the thumb. By spacing the sets of holes as shown in Fig. 1, a thumb hole 15 is disposed alongside one of the finger holes 14, and a thumb hole 16 is disposed alongside of the other of said finger holes 14. It will be seen that one who uses thumb hole 12 for the thumb may insert his second and third fingers in the holes 14-14 and insert the first and 15 little fingers in the thumb holes 15 and 16, respectively. This would be a natural reaction for one who dislikes to curl the unused fingers up to get them clear of the disk.

Between thumb holes 12 and 15 is a pair of finger holes 11-17 which match the thumb hole 16 to form a relatively long span such as would be best suited to a large or a long fingered hand. In a kindred manner a span of intermediate size is provided by the pair of finger holes 18-18 which are spaced from the center of the disk at the same distance as their matching thumb hole 15.

It will now be readily seen that after placing the thumb in the thumb hole which yields the most normal span across the center of the disk, a player may try placing any or all of the fingers in any series of holes that may seem to him most effective or of greatest comfort during such arm, wrist and finger movement as he may put into the act of delivering the disk to slideable movement over the playing surface. The diameter of all holes is sufficiently great to facilitate release of the disk.

The geometric figure 9 may have its points or angles directed toward the several thumb holes, and the numbers 19, e.g., 1, 2 and 3, or any other indicia at these points help find the proper grip after a preferred one is established by the players' choice. The disks may of course be somewhat varied as to size. If the diameter of the disk is greater than the tapered or inclined annular area 11, as herein illustrated, it is preferred to make the outside annular area 20 parallel with the bottom 7, and the disk is thus higher at the center than at the edge.

It will be understood that if the disk be made with its top flat and parallel with the bottom 7 but with the thumb and finger holes arranged as hereinbefore explained and illustrated, the advantages of balance and adaptability to skilled manipulation are retained, but the manufacturing operations in connection with drilling and rounding the edges of the finger and thumb holes would be increased and costlier. From the standpoint of manufacturing costs the illustrated form of disk is preferred, but it will be understood that the invention is not to be considered as limited to the exact arrangement shown, since it may be modified in the spirit of the invention and within the scope of the appended claims.

What is claimed is:

1. A game element comprising a thick flat bottomed disk shaped body having in its top a thumb hole and a relatively opposed pair of finger holes, all of said holes being relatively deep and substantially equidistant from the vertical axis of the disk and undercut toward said axis the centers of the finger holes also being disposed equidistant from and on opposite sides of a diameter of the disk which passes through the center of the thumb hole.
2. A game element comprising a flat bottomed disk having in its top a plurality of thumb holes spaced apart on different radii of the disk and at different distances from the center of the disk and also having, relatively opposite each of the respective thumb holes, a pair of finger holes spaced a like distance from the center of the disk, all of the holes being undercut toward the center of the disk, whereby a user may utilize a selected thumb hole for his thumb and any of the remaining thumb and finger holes for his fingers.
3. A game element comprising a generally flat disk provided with a concentric annular portion on its top face inclined downwardly toward the outer edge at an angle of about ten degrees (10°), said disk having a plurality of thumb holes and pairs of finger holes opposite them and equidistant therewith from the axis of the disk, the respective thumb holes angularly spaced about the axis of the disk and at different distances therefrom.
